SALES PAD

Hugh C. Alexander, New York, N. Y.

Application April 18, 1934, Serial No. 721,086

5 Claims. (Cl. 282—8)

This invention relates to sales pads and the like and my improvements are directed to means for rendering these devices of greater usefulness than heretofore.

5 One of the objects of my invention is to provide means whereby, without extra labor, a day or chronological sales record may be automatically produced at the time of preparing the usual duplicate invoices, thereby assuring accuracy, and saving the labor and time of transcription.

A further object is to provide, by means of the chronological sales record, a mailing list of customers with their addresses and other useful data.

15 A still further object of my invention is to arrange the reverse side of the chronological sales sheet for an identified analysis or other distribution of the sales thereof, and for including said sheet in a loose leaf binder.

20 Other features and advantages of my invention will hereinafter appear.

In the drawings:—

Figure 1 is a top perspective view of a pad, closed, containing my improvements.

25 Fig. 2 is a bottom perspective view of the same.

Fig. 3 is an exploded perspective view of the pad elements.

Fig. 4 is a section on the line 4—4 of Fig. 1.

30 Fig. 5 is a perspective view of the pad with the guide element detached.

Fig. 6 is a perspective view of the pad with the chronological sheet shifted and in use.

Fig. 7 is a perspective detail of the chronological sheet with its connected slide member.

35 Fig. 8 is a perspective detail of a duplicate invoice.

Fig. 9 is a perspective view of a complete sales pad, in use, showing a modified means of operation.

40 Fig. 10 is a perspective view of my improved sales pad, showing a modified form of guide strap, also showing the loose leaf binding for the chronological sheets.

Fig. 11 is an exploded perspective view of the sales pad elements, and

45 Fig. 12 is a detached perspective view of the pad and slide elements, the pad having an extra carbon element, and the slidable element having pairs of chronological sheets.

50 Referring first to the subject matter of Figs. 1 to 8, let 1 indicate a pad backing upon which is imposed and secured a stack of duplicate invoice sheets and a carbon sheet interleaving therewith in the usual manner.

55 The usual pad backing sheet is also shown at X.

The permanent invoice sheet, which is the one to receive the carbon copy, is indicated at 2; the customer's sheet, which is to be detached in the usual manner, is indicated at 3, and the carbon sheet at 4.

5 It will be noted that sheet 3, which is in the usual manner detachable at its bottom 5 from sheet 2, is shorter in length than sheet 2, it having no top portion, like sheet 2, on which to write the name and address of the customer. This is because an additional sheet, indicated at 6, carried by a slide member 7 which is provided with a tongue portion 8, is caused to lie over the carbon sheet 4 and partially under the invoice sheet 3, so that when writing out an invoice or sales slip 10 the name and address of the customer, with any other desirable information, will appear on sheet 6 and the carbon copy thereof on sheet 2, but sheet 3, which is to be detached and given to the customer, being of shorter length than sheet 2, 20 will be devoid of the name and address.

The sheet 6 is shiftable, in a manner to be described hereinafter, so that when the name and address of the customer have been written as stated, and the articles sold itemized on the duplicate invoice sheets and sheet 3 detached, then sheet 6 is to be shifted to bring succeeding lines thereon or a suitable space on which to write the name and address of the next customer. 25

The stack of sheets forming the pad is united 30 at one end by a binding strip 9 and stapling or other fastening means 10 is employed to connect the backing sheet to the pad. The strip 9 has extended fingers 11 that fold over at the back of the pad and form a loop which is adapted to slidably engage the tongue 8 when the pad is in use; although, in Fig. 4, as in Figs. 1 and 2, with the pad closed, the slidable member 7 is shown reversed.

35 The strip 9, besides having fingers 11, also has fingers 12, which fold over the front of the pad and are secured together to form a loop for its reception and frictional engagement. The strip 9 also has front and rear flaps 13, 14 that enclose the top end of the pad and are secured thereto 40 as by the staples 10.

45 The flap 14 of strip 9 does not enclose the backing 1, which, as shown in Fig. 5 is spread apart from the pad, at its upper end for the reception of said flap, prior to the stapling together of these elements.

50 In Fig. 3 the slidable member 7 is shown separated from the pad, and with its tongue 8 in readiness to be slipped through the loop formed by fingers 11 at the back of the pad. The tongue 55

is thus entered to bring the fold 15, between member 7 and tongue 8, against the top of the pad, and the sheet 6 is to be slipped through the loop formed by fingers 12, so that said sheet 6 5 will overlie the carbon sheet 4 and underlie the invoice sheet 3, see Fig. 6.

The pad is now in readiness for use and the user may write out on the top lines or space of sales record sheet 6 the name and address of a 10 customer, together with such indicia in the margin as may be desirable in establishing a sales record. Then upon the short invoice sheet 3 the user may write out the list of items sold or ordered, placing the prices and total thereof in 15 the margin, as is the custom with ordinary sales pads, and this writing on invoice sheet 3, as well as the writing on sales record sheet 6 will be transferred upon the invoice sheet 2. Sheet 3 is to be detached at 5 and handed to the customer, and sheet 2 is to be detached from the pad and re- 20 tained.

Sheet 6 is now to be shifted to bring the next 25 succeeding lines or space in position beyond the succeeding invoice sheet 3 in order that the next customer's name and address may be written on said lines or space and a duplicate invoice prepared in the same manner as before. To so shift sheet 6 the shiftable member 7 with its tongue 8 is slid through the loop formed by fingers 11 30 a sufficient distance to cause said sheet 6 to roll over the top of the pad and be drawn upwardly through the loop formed by fingers 12 to thus position the succeeding name and address lines or space just above the top of said succeeding 35 sheet 3. The shiftable member 7 may have a number of sheets 6 attached thereto, and when one of these sheets has been filled with names and addresses, to thus constitute a chronological record, it may be detached and filed and the next 40 succeeding sheet 6 then slid under the loop formed by fingers 12, to be used in the same manner.

As will be noted in Figs. 6, 7 and 8 the chronological sheets 6 each bear a number of columns 45 which may be used to write in desirable data, as for example under the headings of Date—Customer—Dept.—Amt. Such data are of course only arbitrarily selected, and may be varied to suit the needs of the trade. Also each heading space or 50 line is given a number on sheet 6, these numbers being consecutively arranged and intended as indicia for the purpose of identifying the customer and the particular purchases with an analysis thereof that is to be provided on the reverse side of the chronological sales record sheet, as 55 will be described hereinafter with reference to Figs. 10 and 11. Since the duplicate invoices are also numbered in the same order, the chronological sales record gives an accounting of both 60 invoices and distribution.

In Fig. 9 the same pad and shiftable elements for the chronological record are shown, but here the sheet 6 is placed and secured the reverse way 65 on shiftable member 7, and said member, instead of its tongue 8, is to be introduced through the guide loop 11; the sheet 6, instead of being rolled over the top end of the pad, being entered directly through its guide loop 12. With this modification the member 7, with sheet 6, will be drawn 70 outwardly in advancing said sheet to bring a succeeding space or line into position to serve for an invoice heading.

In Figs. 10 and 11, instead of the flexible strip 9, with its loop forming fingers 11, 12 I provide 75 a metallic strap 16, having lugs 17 by which it

is secured to a stiff backing sheet 18, said strap having a bar 19 that divides it into two loops, 20, 21, the loop 20 being bounded by the top of strap 16 and bar 19, and the loop 21 being bounded by bar 19 and the surface of backing sheet 18. 5

In using this strap the tongue 8 of shiftable member 7 is slid through the loop 21, and the sheet 6, which is rolled over the top end of the pad, is slid through the loop 20, which loop 20 also receives the top end of the pad, said pad being localized in loop 20 by reason of the fact that its backing sheet 1 has been engaged in the loop 21. 10

The operative employment of the pad under this modification is the same as in the instance of the example illustrated in Figs. 1 to 8. 15

Also in Fig. 10 I have shown a stiff backing member 22, coupled to backing 18 as by split rings 23, in the manner of a loose leaf binder, and the sheets 6 are perforated that they may be connected to said member 22 as loose leaves. 20

To accord said sheets 6 added utility they may bear on their reverse sides the heading of sales analyses, with suitable sub-headings such for example as dep. for department, so that in vertical columns under respective sub-headings, and in horizontally disposed spaces which extend from numeral indications at the left, the numbering, which is consecutive, corresponds with the numbering on the chronological sales record side of the sheet, whereby the sales analyses at said reverse side of sheet 6, which may be written out from the sales data on the respective invoice sheets, constitutes an itemized record or summary of the sales to all the customers represented on the chronological sales record side of sheet 6. 30

A still further modification is illustrated in Fig. 12, wherein pairs of chronological sales record sheets are shown at 24, 25, the sheet 24 corresponding to sheet 6, but the underlying sheet 25 40 of the pair being of thin, highly transparent paper. The sales pad, at its top, carries an extra, short carbon sheet 26, whose carbonized surface is uppermost, said carbon sheet 26 extending down the pad only to the point where it may meet 45 the top edge of invoice sheet 3, but without overlapping sheet 3. Thus in writing the customer's name and address with such added indication as may be desired, upon sheet 6, this writing will by means of carbon sheet 26 be produced, backwards upon the under surface of transparent sheet 25, but may be read the right way through said sheet. Therefore at one writing the user can produce the chronological sheet in duplicate, in addition to performing the previously stated 50 functions of the device. The extra copy of the chronological sales sheet may be used as a tally for the sales clerk, by having each section perforated, by which means the extra copy may be divided at any section, and the completed section 55 can be turned in at the end of the day while the lower or unfilled portion can be retained in the sales pad for future use. This extra copy of the chronological sales record may be used for such other purposes as the trade may require. 60

While my improvement has been described and illustrated with respect to sales or invoice sheets it is obviously equally applicable to other analogous uses.

Variations within the spirit and scope of my 70 invention are equally comprehended by the foregoing disclosure.

I claim:—

1. A sales pad having folded invoice sheets interleaved with a carbon sheet wherein the outer 75

5 invoice sheet is of less length than the inner invoice sheet, and a super sheet that is adapted to lie between said invoice sheets, a stiff backing sheet connected with said super sheet; guide means at the back of the pad for the slidale reception of said backing sheet, and guide means at the front of the pad for said super sheet, whereby the shifting of the backing sheet also shifts said super sheet, said super sheet being adapted 10 to have data written thereon in chronological order for carbon transcription respectively only upon succeeding inner invoice sheets.

15 2. A sales pad having folded invoice sheets interleaved with a carbon sheet wherein the outer invoice sheet is of less length than the inner invoice sheet, a fixed strap having upper and lower loops, said pad being adapted for reception in said upper loop, a stiff back sheet for said pad adapted for lodgement in said lower loop to localize 20 said pad, a super sheet that is adapted to lie between said invoice sheets, a stiff backing sheet connected with said super sheet and adapted to be slidably engaged in said lower loop while said super sheet is slidale in said upper loop, whereby 25 said super sheet is shiftable with the shifting of its backing sheet, said super sheet being adapted to have data written thereon, in chronological order, for carbon transcription respectively only upon succeeding inner invoice sheets.

30 3. A sales pad having folded invoice sheets interleaved with a carbon sheet wherein the outer invoice sheet is of less length than the inner invoice sheet, an extra carbon sheet of short length that lies carbon side uppermost, over the 35 top portion only of the inner invoice sheet, and a pair of super sheets, of which the under sheet is transparent, adapted to lie over said inner invoice sheet and to be shiftable thereon, the outer

one of said pair of super sheets being adapted to have data written thereon, in chronological order, for carbon transcription respectively upon succeeding inner invoice sheets, and for transcription backwards upon the under side of the 5 said transparent super sheet.

4. A pad composed of folded sheets each having inner and outer leaves, whereof the inner leaf has a weakened line near its end for detachment and the outer leaf is shorter than said inner leaf 10 to expose a heading space on said inner leaf, between the end of said outer leaf and the end of the detachable inner leaf, where it is weakened, a super sheet that is shiftable relatively to the pad over said inner leaf and adapted to have data 15 written thereon in chronological order, and a carbon sheet interposed between said inner and outer leaves and between said super sheet and the exposed heading space on said inner leaf, whereby the chronological data will be transcribed on said exposed heading space of said inner leaf only.

5. A pad composed of folded sheets each having inner and outer leaves, whereof the inner leaf has a weakened line near an edge thereof for 25 detachment and the outer leaf is shorter than said inner leaf to expose a heading space on said inner leaf, between the end of said outer leaf and the end of the detachable inner leaf, a super sheet that is shiftable relatively to the pad over 30 said inner leaf and adapted to have data written thereon in chronological order, and a carbon sheet interposed between said inner and outer leaves and between said super sheet and the exposed heading space on said inner leaf, whereby 35 the chronological data will be transcribed on said exposed heading space of said inner leaf only.

HUGH C. ALEXANDER.
